UNITED STATES PATENT OFFICE.

ABRAHAM ZWIEBELSON, OF NEW YORK, N. Y.

BRASSIÈRE.

Application filed October 19, 1922. Serial No. 595,591.

To all whom it may concern:

Be it known that I, ABRAHAM ZWIEBELSON, a citizen of the United States, and a resident of the city of New York, borough of Manhattan, in the county and State of New York, have invented a new and Improved Brassière, of which the following is a full, clear, and exact description.

This invention has relation to wearing apparel and refers more particularly to an improvement in brassières.

The invention contemplates for its principal object a brassière which is provided with means for effectively encasing the body of the wearer, and which conforms to the movement of the body, while at the same time preventing its displacement as well as the displacement of the corset.

As a further object the invention provides a new and improved brassière which is especially designed for wear by stout women and is so designed as to produce pressure against the diaphragm and the front and median portion of the wearer's body and to exert a uniform pressure directly under the bust for properly supporting the internal organs, which have a tendency to droop especially after childbirth.

The invention further contemplates a brassière which constitutes an appliance for promoting the proper distribution of the fat roll of the upper abdomen and which tends to further distribute the same below the breast and flare of the ribs.

As a still further object the invention contemplates a brassière which is simple in its construction, inexpensive to manufacture and which is thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the full extent indicated by the general meaning of the terms in which the claims are expressed.

In the drawings—

Figure 1 is a rear perspective view of the brassière applied.

Fig. 2 is a front perspective view of the same.

Fig. 3 is an enlarged inner face elevation of the brassière in opened position.

Fig. 4 is a fragmentary horizontal sectional view taken on the line illustrated at 4—4 of Fig. 3.

Fig. 5 is a similar view on the line 5—5 of Fig. 3.

Fig. 6 is a similar view on the line 6—6 of Fig. 3.

Referring to the drawings by characters of reference, the body of the brassière is preferably constructed from a single length of inelastic material 10, the opposite end edges 11 and 12 of which are provided with interengagable fastening elements. Adjacent the opposite ends the material is vertically plaited as at 13 to receive between the folds thereof one end of an elastic strip 14, which is secured in place by the lines of stitching 15 which form the plait. The opposite end of the elastic strip is attached between the inwardly folded end by the line of stitching 16 which holds said inturned end in place. This forms yieldable portions which when the brassière is arranged in place will lie in the central portion of the back of the wearer. The medial portion of the front of the brassière is provided with spaced parallel plaits 17 between the folds at the inner side of which the opposite ends of crossed elastic strips 18 are arranged, said ends being secured in place by the lines of stitching 19 which form the plaits. Under this arrangement a yieldable portion is provided at the front of the brassière which is disposed under and between the bust for properly supporting the same. This yieldable portion also serves to compensate for the expansion and contraction of the chest to allow for comfortable breathing, while at the same time preventing displacement of the garment. The opposite under side edges of the strip 10 are provided with V-shaped notches 20 which are spanned by elastic gussets 21 for the purpose of contracting the lower edge about the waist of the wearer to prevent riding up of the brassière and at the same time to hold the corset and other undergarments against displacement. A non-elastic strip or tape 22 extends from one V-shaped notch 20 to the opposite V-shaped notch for the purpose of limiting the stretching action of the lower part of the body 10 of the brassière.

Under the foregoing arrangement it will

be seen that a brassière is provided which includes a plurality of elastic elements distributed longitudinally of the body portion thereof in substantially staggered relation 5 to set up a combined contractive action in various horizontal planes whereby to properly encase and support the body of the wearer, to allow for the free movements of the body of the wearer and to retain the 10 brassière in place as well as the corset and other undergarments underlying the same.

I claim:

1. As a new article of manufacture, a brassière comprising a length of inelastic 15 material adapted to encircle the body of the wearer and be detachably connected at its opposite ends at the rear, elastic elements connected to said material for creating a normally slack medial front portion, said 20 elastic elements consisting of crossed elastic strips attached at their opposite ends to the inner face of the medial front portion of the brassière, longitudinally extending elastic strips attached at their opposite ends to the 25 inner face of the medial rear portion of the brassière, and elastic gussets in the lower edge and at opposite sides of the brassière.

2. As a new article of manufacture, a brassière comprising a length of inelastic 30 material adapted to encircle the body, elastic elements connected to said material for creating a normally slack medial front portion, said elastic elements consisting of crossed 35 elastic strips attached at their opposite ends to the inside of the medial front portion of the brassière, longitudinally extending elastic strips attached at their opposite ends to the inside of the medial rear portion of the brassière, elastic gussets in the lower edge 40 and at opposite sides of the brassière, and a non-elastic strip connected to and extending from one gusset to the other.

3. As a new article of manufacture, a brassière including a body member consisting 45 of a length of inelastic material having interengageable means at the opposite ends thereof for maintaining the same in encircling relation on the wearer's body, parallel vertical plaits located at the sides of the 50 medial front portion, crossed elastic strips having their opposite ends secured between the inner folds of said plaits to lie on the inner face of the body member, the lower edges at the opposite sides of said body having 55 V-shaped notches formed therein, elastic gussets in said notches, and elastic strips secured within the medial rear portion of said

body, all of said elastic elements serving to set up a combined contractive action in various horizontal planes for properly encasing and supporting the body of the wearer. 60

4. As a new article of manufacture, a brassière including a body member consisting of a length of inelastic material having interengageable means at the opposite ends 65 thereof for maintaining the same in encircling relation on the wearer's body, parallel vertical plaits formed in the medial front portion, crossed elastic strips having their opposite ends secured between the inner folds 70 of said plaits to lie on the inner face of the body member, the lower edges of the opposite sides of said body having V-shaped notches formed therein, elastic gussets in said notches, a nonelastic strip extending 75 from one of said V-shaped notches to the opposite one, and elastic strips secured within the rear medial portion of said body, all of said elastic elements serving to set up a combined contractive action in various horizontal planes for properly encasing and supporting the body of the wearer. 80

5. As a new article of manufacture, a brassière including a body member consisting of a single length of inelastic material 85 having its opposite ends inwardly folded and provided with interengageable means at said ends for maintaining the same in encircling relation on the wearer's body, vertical plaits formed in said body member adjacent its opposite ends, parallel vertical plaits formed in the medial front portion of the body member, obliquely crossed elastic strips having their opposite ends secured between the inner folds of said last mentioned 90 plaits to lie within the body member to normally form a slack section at said medial front portion, the lower edges of the body member having V-shaped notches formed 95 therein at each side of said front portion, elastic gussets in said notches, a non-elastic strip connected to the inner edges of said notches and extending across the said front portion within the body member, and an elastic strip secured at its opposite ends 100 within the inwardly folded ends and the inner fold of the vertical plait adjacent said ends at the medial rear portion, all of said elastic elements serving to set up a combined contractive action in various horizontal 105 planes for properly encasing and supporting certain organs of the body of the wearer. 110

ABRAHAM ZWIEBELSON.
